(57) **CLAIM**

The ornamental design for a shaft for a handled tool, as shown and described.

DESCRIPTION

FIG. 1 is a perspective view of the shaft for a handled tool in accordance with the present invention;

FIG. 2 is a top view of the shaft for a handled tool;

FIG. 3 is a bottom view of the shaft for a handled tool;

FIG. 4 is a side view of the shaft for a handled tool; and,

FIG. 5 is a cross-sectional view of the shaft for a handled tool

taken in the direction of lines 5-5 in FIG. 4.

The portions of the design shown in broken line—including the handle, the interior of the shaft, and the tool head—are for reference only and form no part of the claimed design.
